Primary Examiner — Darcey E Gottschalk*Assistant Examiner* — Vanessa M. Pursley**CLAIM**

The ornamental design for an insulated package with an auto-lock bottom, as shown and described.

DESCRIPTION

FIG. 1 is a top isometric view of an insulated package with an auto-lock bottom;

FIG. 2 is a bottom isometric view thereof;

FIG. 3 is a top plan view thereof;

FIG. 4 is a bottom plan view thereof;

FIG. 5 is a front plan view thereof;

FIG. 6 is a rear plan view thereof;

FIG. 7 is a left-side plan view thereof;

FIG. 8 is a right-side plan view thereof; and,

FIG. 9 is a semi-flat configuration view thereof.

The right-side plan view is a mirror image of the left-side plan view.

The rear plan view is a mirror image of the front plan view.
